CLAIM

The ornamental design for transparent tumor size measuring ruler with transparent slider, as shown and described.

DESCRIPTION

FIG. 1 is top perspective view of the transparent tumor size measuring ruler with transparent slider; and

FIG. 2 is a top view of the transparent tumor size measuring ruler with transparent slider of FIG. 1.

FIG. 3 is a top perspective view of a second embodiment of the transparent tumor size measuring ruler with transparent slider;

FIG. 4 is a top view of the transparent tumor size measuring ruler with transparent slider of FIG. 3;

FIG. 5 is a top perspective view of a third embodiment of the transparent tumor size measuring ruler with transparent slider;

FIG. 6 is a top view of the transparent tumor size measuring ruler with transparent slider of FIG. 5;

FIG. 7 is another top perspective view of a fourth embodiment of the transparent tumor size measuring ruler with transparent slider; and,

FIG. 8 is a top view of the transparent tumor size measuring ruler with transparent slider of FIG. 7.

The short dash broken lines, the long dash broken lines, and the dot-dash broken lines illustrating portions of the transparent tumor size measuring ruler with transparent slider form part of the claimed design.
